United States Patent Office

Des. 225,846
Patented Jan. 9, 1973

225,846

BLOCK

Harry F. Cruzen, Jr., Alpena, Mich., assignor to
Besser Company, Alpena, Mich.

Continuation of design application Ser. No. 13,725, Sept.
26, 1968. This application Mar. 23, 1970, Ser. No.
22,002

Term of patent 14 years

Int. Cl. D25—01

U.S. Cl. D18—2

Fig. 1

Fig. 2

Fig. 3

Fig. 4

Fig. 5

FIG. 1 is a perspective view of the block;
FIG. 2 is a top plan view thereof;
FIG. 3 is a sectional view thereof, taken on the line
3—3 of FIG. 2; and
FIG. 4 is a transverse, sectional view, taken on the line
4—4 of FIG. 2.
FIG. 5 is an end elevational view.

This application is a continuation of my earlier filed design patent application Ser. No. 13,725, filed Sept. 26, 1968, and now abandoned.

I claim:
The ornamental design for a block, substantially as shown.
